(57) **CLAIM**

The ornamental design for an elevator operating panel, as shown and described.

DESCRIPTION

FIG. 1 is a front perspective view of our elevator operating panel.

FIG. 2 is a back perspective view thereof.

FIG. 3 is a back view thereof.

FIG. 4 is a bottom view thereof.

FIG. 5 is a front view thereof.

FIG. 6 is a left side view thereof, with the right side being a minor image; and,

FIG. 7 is a top view thereof.

The broken lines in the drawings show features of the elevator operating panel that form not part of the claimed design.

1 Claim, 7 Drawing Sheets
